ROTARY SWAGING MACHINES

Samuel Smith, Elmdon, England

Application July 1, 1952, Serial No. 296,694

1 Claim. (Cl. 78—22)

The present invention has relation to rotary swaging machines. Rotary swaging machines have been proposed comprising a stationary head having a rotary flywheel and radial dies and co-operative radial hammer blocks have been provided in the stationary head displaceable by rollers in the flywheel for swaging purposes. Other rotary swaging machines have comprised a stationary annulus with rollers and a rotary head within the annulus and rollers and with radial dies and hammer blocks for swaging purposes. In each instance cotters, keys, wedges or like devices have been accommodated partially within the hammer block and partially within the head for generally controlling and limiting the movement of the hammer blocks and the present invention is particularly concerned with these cotters, keys, wedges or like devices and their housings, the objective being to so construct the said device that, primarily, they shall provide for less noise particularly when the machine is operating freely without a workpiece, which normally causes a clatter between the hammer blocks and the rollers associated with the moving part.

According to the present invention there is provided a rotary swaging machine having cotted, key, wedge or like device, or alternatively a cotted, key, wedge or like device for use upon a rotary swaging machine which is of a resilient expansible character adapted to engage the hammer block and head and provide means whereby the hammer block is normally held away from contact with the operative rollers when the associate dies are not actually in operation on the workpiece.

Conveniently a channel shaped member is adapted to slide within a cavitated block with the intermediary of rubber, spring or the like and this device is inserted in registering parallel sided slots in the head and the hammer block, the arrangement being such that the latter are normally held away from the rollers when the machine is running idle and noise and clatter thereby avoided or reduced.

In order that the invention may be clearly understood and readily carried into practice reference may be had to the appended explanatory drawings in which:

Fig. 1 illustrates the operative part of a rotary swaging machine incorporating silencing devices in accordance with the present invention, the workpiece being in position.

Fig. 2 is a similar view with workpiece removed, the silencing devices taking effect.

Fig. 3 illustrates a hammer block and shows the installation therein of the combined silencing device and key.

Fig. 4 is a view in perspective of the hammer block without the combined silencing device and key.

Fig. 5 is a transverse sectional view of the hammer block with the combined silencing device and key inserted in a keyway or slot in the side of the hammer block, and

Fig. 6 is an exploded view in perspective of the combined key and silencing device.

2

In a convenient embodiment of the present invention there is provided a rectangular or oblong block of metal *a* having a rectangular cavity on its under side. Adapted to slide within the mouth of this cavity is a channel-

6 shaped member *b* of sheet metal or the like and interposed between the two parts is a rubber buffer *c*. The block of metal *a*, the channel shaped sheet metal member *b* and the rubber buffer *c* constitute a combined silencing device and key. Provided in the side of the hammer block *d* and in the side of the head *e* are parallel slots *d*¹, *e*¹ and this combined silencing device and key *a*, *b*, *c*, is incorporated partly within each slot, and thus housed and protected and constrained against toppling out of place. It will be appreciated that its resilience permits the hammer blocks *d* to do their normal work (Figure 1) and when there is no workpiece in the machine (Figure 2) the hammer block *d* is urged away from the rollers *f* so that there is no succession of impacts and noise or clatter is thereby avoided. As previously intimated the device is applicable to either type of rotary swaging machine, that is to say, a rotary swaging machine comprising a fixed head and rotary flywheel or a rotary swaging machine comprising a fixed annulus and internal rotary head. The hammer blocks have cylindrical inserts *g* of hard metal which engage the rollers *f*. The hammer blocks are displaced towards the rollers against the compression action of the resilient devices by means of wedges interposed between the hammer blocks and the work. Such wedges and cylindrical inserts of hard metal are well known in the art.

30 I claim:

A combined retaining and retracting device for swaging machine hammer blocks which have parallel sides and are slidably fitted between parallel walls in a swaging machine head, said combined retaining and retracting device comprising a rectangular key member having a rectangular cavity extending across one side thereof, the ends of said cavity being perpendicular to the sides of said key member, a rectangular strip having its ends bent at right angles to the sides of said strip, the ends of said strip so bent 35 being fitted slidably between the ends of said cavity, and a rectangular resilient cushion fitted between the ends of said strip, the thickness of said cushion being greater than the distance to which the ends of said strip extend perpendicularly from the sides of said strip, whereby said strip is resiliently held outwardly of the side of said key member, there being keyways in the sides of said hammer blocks and in the walls of said swaging machine head between which said hammer blocks are slidably fitted, the keyways in the sides of said hammer blocks and the keyways in said walls of said swaging machine head being in 40 registration when said hammer blocks are retracted, the composite thickness of said key member, said strip and said cushion being substantially equal to the width of said keyways when said hammer blocks are retracted and said keyways are in registration, said resilient cushion being confined between the back walls of registering keyways as well as between one of said key members and one of 45 said strips, but said resilient cushion being capable of yielding to permit said hammer blocks to move outwardly when forced to do so incident to the insertion of work to be acted upon by said hammer blocks.
